United States Patent Office

Des. 178,553
Patented Aug. 14, 1956

178,553

WOMAN'S SHOE

Otto F. Stock, Columbus, Ohio, assignor to The Julian and Kokenge Company, Columbus, Ohio, a corporation of Ohio

Application March 26, 1956, Serial No. 40,762

Term of patent 14 years

(Cl. D7—7)

FIG. 1.

FIG. 2.

FIG. 3.

FIG. 4.

Fig. 1 is a perspective view of a woman's shoe showing my new design;

Fig. 2 is a top plan view;

Fig. 3 is a bottom plan view; and

Fig. 4 is a side elevational view thereof.

I claim:

The ornamental design for a woman's shoe, substantially as shown.
